UNITED STATES PATENT OFFICE.

THOMAS E. ELLERBY, OF SENECA FALLS, NEW YORK.

DESIGN FOR AN INKSTAND AND PEN-RACK.

SPECIFICATION forming part of Design No. 17,456, dated July 19, 1887.

Application filed May 25, 1887. Serial No. 239,361. Term of patent 7 years.

To all whom it may concern:

Be it known that I, THOMAS E. ELLERBY, a citizen of the United States, residing at the village of Seneca Falls, in the county of Seneca, in the State of New York, have invented and produced a new and original Design for an Inkstand and Pen-Rack, of which the following is a specification, reference being had to the accompanying photographic illustrations, forming a part thereof.

Figure 1 is a view of the right and front sides of my newly-designed inkstand and pen-rack. Fig. 2 is a view of the left side and back of the same, the two views being deemed necessary to fully illustrate my design.

The base represents a marine fortress, the cap or cover being a representation of a military cap. Fig. 1 also gives a view of the right side, which comprises a representation of a cannon at the base, with a haversack and canteen in relief, three muskets, a cannon upright at the back, all surmounted by a swab-stick and cannon-balls.

Fig. 2 gives a view of the left side, which comprises a representation of a life-boat, a capstan surmounted by an anchor, and four marline-spikes, with a cannon upright at the back; also a view of the back, which comprises a representation of two swords crossed, surmounted by a representation of a picket on duty, and a citizen on a mule, comprising a group peculiar to army life.

Fig. 1 is a view of the front and right side, which comprises the representation of the marine fortress, the military cap in the front, and the right side comprises the cannon at the base, the canteen and haversack in relief, the three muskets, the cannon upright at the back, the swab-stick, and the cannon-balls surmounting the muskets.

Fig. 2 is a view of the left side and back. The left side comprises a representation of a life-boat, a capstan surmounted by an anchor, and four marline-spikes, with a cannon upright at the back. The back comprises a representation of two swords crossed, surmounted by a representation of a citizen on a mule and of a picket on duty, forming a group peculiar to army life.

I claim as my invention—
The design for an inkstand and pen-rack, as herein described and shown, the same consisting of a base representing a marine fortress with top simulating a soldier's cap, and having grouped on the sides thereof horizontal and upright cannon, wheel, anchor, muskets, swab-stick, cannon-balls, life-boat, and other navy and army equipments, with a back comprising a group peculiar to army life mounted over crossed swords, as set forth.

THOMAS E. ELLERBY.
